CLAIM

We claim the ornamental design for an outsole for a boot, shoe, footwear, or the like, as shown and described.

DESCRIPTION

FIG. 1 is a perspective view of an outsole for a boot, shoe, footwear, or the like showing the new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged bottom plan view thereof, showing the sole portion of FIG. 8.

The broken lines adjacent to the shaded areas depict boundaries of the claim and form no part of the claimed design. The dash-dot-dash broken lines depict boundaries of the claim and form no part of the claimed design. All other broken lines illustrate unclaimed portions of the outsole for a boot, shoe, footwear, or the like, as well as the boot environment, and form no part of the claimed design.
